FEED AND DISCHARGE MECHANISM FOR
CONTAINER HANDLING MACHINESFrank W. Krueger, Atherton, Calif., assignor to
Food Machinery and Chemical Corporation, a
corporation of Delaware

Application July 3, 1944, Serial No. 543,339

10 Claims. (Cl. 226—96)

1

This invention relates to handling of containers as is necessary in filling and capping these.

For operations of filling or capping containers such as cans, jars and bottles, there is commonly employed a rotary processing mechanism onto which the container is fed and from which it is delivered after the filling or capping process has been performed. In some of these mechanisms the container is elevated to fill or cap this container while it is on such a rotary mechanism and the container then lowered prior to its discharge from the mechanism.

Various devices have been offered for feeding containers to and discharging them from such a rotary mechanism and it is an object of this invention to provide an improved device for performing this function.

The manner of accomplishing the foregoing object, as well as further objects and advantages, will be made manifest in the following description taken in connection with the accompanying drawings in which:

Fig. 1 is a diagrammatic plan view of an improved embodiment of the invention incorporated with a jar capper, this view being taken on the line 1—1 of Fig. 2.

Fig. 2 is a diagrammatical fragmentary sectional view taken on the line 2—2 of Fig. 1.

Fig. 3 is a development of a cam employed for vertically reciprocating the container carrying tables of said invention.

Fig. 4 is a fragmentary perspective view of the jar capper shown in Fig. 1 and showing jars in different elevated positions therein.

Fig. 5 is an enlarged fragmentary plan view taken on the line 5—5 of Fig. 4 and illustrating the transfer of jars from the feed runway onto the elevator tables of the invention.

Fig. 6 is a still further enlarged fragmentary elevational view taken on the line 6—6 of Fig. 5 and illustrating the manner in which a jar pusher of the invention is mounted on the conveyor chain thereof.

Fig. 7 is a further enlarged horizontal sectional view taken on the line 7—7 of Fig. 6 and illustrating the details of said mounting.

Referring specifically to the drawings, these show a jar capper 10 having a frame 11 on which a rotor 12 is rotatably mounted on a power driven vertical shaft 13. The rotor 12 carries a series of capping heads 14 for capping containers such as jars 15 which are fed to and discharged from the rotor by a feed and discharge mechanism 16.

The rotor 12 has a hub 20 (see Fig. 2) on which is mounted a notched jar locating disc 21, a

2

sprocket 22 having openings 23 therein, and an elevator unit 24.

The elevator unit provides a series of bores 25 in each of which an elevator plunger 26 is slideably disposed, the lower end of each plunger carrying cam following rollers 27. These ride against annular cam tracks 28 and 29 which define a cam path 30, an elevation development of which is shown in Fig. 3. This cam path includes a low portion 31 and a high portion 32.

Each of the elevator plungers 26 has a neck 35 which extends upwardly through one of the openings 23 in the sprocket 22 and supports a container carrying table 36 on its upper end.

15 The container feed and discharge mechanism 16 includes sprockets 40, 41 and 42 which lie in the same horizontal plane as the sprocket 22, and a chain 43 is trained about these sprockets as shown in Fig. 1. This chain carries a series of 20 jar pushers 44 which extend upwardly therefrom and travel between stationary horizontal tracks 45 flanked by guides 46 and 47 to form a jar runway 48. Any suitable delivery device such as the delivery wheel 49 shown in Fig. 1 may be employed to deliver jars 15 onto the runway 48 so that one jar is disposed just in advance of each of the pushers 44.

25 The tracks 45 are on substantially the same level as each of the tables 36 when the latter is in its lowermost position by virtue of its rollers 27 traveling in the low portion 31 of the cam path 30. These tracks 45 end, as shown in Fig. 1, just outside of the path followed by the tables 36 as they rotate with the rotor 12. The jars 15 are thus fed by the pushers 44 from the ends of the tracks 45 onto the respective tables 36 as these arrive opposite the tracks 45.

30 As each table 36 continues to travel with the rotor 12, the rollers 27 of this table enter the high portion 32 of the cam path 30 thereby elevating this table to introduce the jar 15 carried on that table into the capper head 14 disposed immediately thereabove. The capping operation is accomplished in about 180 degrees of rotation of the rotor 12 after which each table 36 is lowered by the rollers 27 thereof descending into the low portion 31 of the cam path 30. This occurs as each table 36 approaches the sprocket 40.

35 Provided on the frame 11 of the jar capper 10 to divert capped jars from the tables 36, is a discharge chute 55 having a bottom 56 which is channeled to permit the pushers 44 to pass therethrough and which extends close to the path traveled by the lowered tables 36 on the rotor 12 and lies on substantially the same level as the

lowered tables. The discharge chute 55 has side-walls 57 and 58 which extend inwardly beyond the inner end of the chute bottom 56 to engage and guide jars 15 so that they will remain in front of the pushers 44 as the latter travel about the sprocket 40.

The capped jars on the lowered tables 36 are thus guided into and discharged along the chute 55 as shown in Fig. 1. The lowered tables continue with the rotor 12, thus being withdrawn from between an adjacent pair of jar pushers 44 and moved in between another pair of these jar pushers to receive another jar being fed along the tracks 45 to the rotor 12.

It is to be noted that the tables 36 and the mechanisms for elevating these never interfere with the chain 43 entering or leaving meshing relation with the sprocket 22 of the rotor 12.

Each of the jar pushers 44 has a finger 70 at its upper end which extends forwardly from the main body 71 of this pusher. Provided on this body below the finger 70 is an adjustable finger 72. The forward ends of fingers 70 and 72 are in the same vertical plane and are of such a length as to contact and position a jar 15 in its proper location on an adjacent elevator table 36.

Some of the jars handled have annular recesses 75 about their middle and when the table 36 is being elevated or lowered it is desired to keep one of the fingers 70 or 72 in contact with the upper and lower portions of larger diameter of the jar whenever the upper end of the jar is not centered in one of the copper heads 14. The finger 72 is separable from and adjustable vertically in any desired manner on the body 71 of the jar pusher 44 so that it will accommodate itself to various jars which vary as to the size and location of the annular recess 75. For this purpose the finger 72 may be secured to the body 71 by a screw 76 and a plurality of vertically spaced screw holes 77 provided in the body 71 to receive said screw.

The jar pushers 44 are adjustably mounted on the chain 43 as shown in Figs. 6 and 7. Here it is seen that each pusher 44 has vertical holes 80 bored upwardly from the lower end in which are received upward extensions of chain pins 81. The pusher 44 is held in place on these chain pins by screws 82 which permit these pushers to be readily removed and replaced by other pushers when this is necessary to adapt the copper 10 for operation on jars of a different size or shape.

Each of the elevator tables 36 is provided with a notch 85 to accommodate the finger 72 when the table rises or is lowered past this finger.

I claim:

1. In a container feed and discharge mechanism, the combination of a rotor adapted to rotate about a vertical axis; a sprocket provided on said rotor concentric with said axis and having openings therein spaced inwardly from the periphery thereof; an endless chain meshing with said sprocket and adapted to travel with the latter about said axis as the rotor rotates; means including a container feed station and a container discharge station and through which said endless chain travels; a series of container elevating tables provided on said rotor; means for feeding and guiding containers from said feed station onto said tables; means for ejecting and guiding said containers from said tables to said discharge station after said containers have revolved a substantial distance with said rotor; means on said chain to propel containers from said feed station along said feeding and guiding means onto said tables and along said ejecting and guiding means

to said discharge station, said tables being disposed above said chain; and means on said rotor disposed inwardly from said chain and operating through said openings in said sprocket to support said tables and to elevate and lower said tables to lift said containers as they revolve with said rotor for performing an operation on said containers, and then to lower said tables and containers to operative relation with said ejecting and guiding means.

5 2. The combination as in claim 1 in which said container propelling means on said chain cooperates with means on said rotor to center said containers on said tables against movement relative thereto when the tables are moved to raised and lowered positions.

10 3. In a container feed and discharge mechanism, the combination of: a rotor adapted to rotate about a vertical axis; a sprocket provided on said rotor concentric with said axis; an endless chain meshing with said sprocket and adapted to travel with the latter about said axis as the rotor rotates; means including a container feed station and a container discharge station through which said endless chain travels; a series of elevating tables provided on said rotor and disposed at all times above said chain; stationary means for feeding and guiding containers from said feed station onto said tables; stationary means for ejecting and guiding said containers from said tables to said discharge station after said containers have revolved a substantial distance with said rotor; means on said chain to propel containers from said feed station along said guide means onto said tables and along said ejecting and guiding means to said discharge station; and means on said rotor for elevating and lowering said tables while the containers are carried thereon, said table elevating means being located out of the path of said chain as the latter travels into and out of meshing relation with said sprocket.

15 4. In a container feed and discharge mechanism, the combination of: a rotor adapted to rotate about a vertical axis; a sprocket on said rotor concentric with said axis; an endless chain meshing with said sprocket and adapted to travel with the latter about said axis as the sprocket rotates; a plurality of elevating tables provided on said rotor; means for reciprocating each of said tables from a lowered position at a level close above said chain to a relatively elevated position to subject a container to an operation while supported on said table; stationary means for guiding a container onto each of said tables when the latter is in lowered position; and stationary means for guiding said container from said table after it has been reciprocated vertically by said table, both of said stationary means for guiding containers onto and from said tables being disposed above the tables when the latter are in their aforesaid lowered positions, said tables and means for reciprocating the same being located at all times out of the path of said chain as the chain travels into and out of meshing relation with said sprocket.

20 5. In a container feed and discharge mechanism, the combination of: a rotor adapted to rotate about a vertical axis; a series of individual elevators on said rotor each of which is adapted to receive and elevate a container to perform an operation thereon and lower said container while the latter is supported on said elevator; a sprocket provided on said rotor concentric with said axis and beneath the lowermost position of said elevators; an endless chain meshing with

said sprocket and adapted to travel therewith about said vertical axis as the rotor rotates; means on said chain extending upwardly therefrom for propelling containers onto and from said elevators, said elevators being located at all times out of the path of said chain as it travels into and out of meshing relation with said sprocket means; and means independent of said chain for supporting said containers as they are propelled towards and from said elevators as aforesaid by 10 said upwardly extending means on said chain.

6. In a container feed and discharge mechanism, the combination of: a rotor adapted to rotate about a vertical axis; a sprocket fixed concentrically on said rotor; an endless container pushing chain traveling towards, about, and away from said sprocket; a series of elevating tables provided on said rotor adjacent the pitch circle of said sprocket; means for vertically reciprocating said tables in timed relation with the rotation of said rotor between an up position and a down position, said down position of the tables being above said sprocket; spaced pusher members fixed on said chain and extending upwardly therefrom; and stationary means for supporting and guiding the containers in the path traversed by said pusher members as the same travel towards and away from said sprocket to cause said pusher members to move said containers onto and from said tables.

7. In a container feed and discharge mechanism, the combination of: a rotor adapted to rotate about a vertical axis; a sprocket fixed concentrically on said rotor; an endless container pushing chain mounted for continuous movement towards, about, and away from said sprocket in a tortuous path of travel; a series of elevating tables provided on said rotor and entirely disposed above said sprocket; means for vertically reciprocating said tables in timed relation with the rotation of said rotor; spaced pusher members provided on said chain respectively extending between adjacent tables when traveling about

said sprocket; and means independently of said chain for supporting and guiding containers in the tortuous path traversed by said pusher members as they travel towards and away from said sprocket to cause said pusher members to move said containers onto and from said tables; and means for vertically reciprocating said tables and their supported containers while the same rotate with said rotor.

8. A combination as in claim 7 wherein said tables are supported on said rotor radially inwardly from said chain to extend radially outwardly to overlie said chain.

9. A combination as in claim 7, wherein said tables are supported radially inwardly on said rotor from said chain and overlie said chain with the pitch circle of said sprocket substantially bisecting the supporting surfaces of said tables.

10. A combination as in claim 6, in which said pusher members propel said containers onto and off of said tables while remaining in contact with the containers throughout the period that the latter rest on said tables and rotate with said rotor, said pusher members cooperating with means on said rotor to center said containers on said tables while the latter are in elevated and depressed positions.
